UNITED STATES PATENT OFFICE.

WILLIAM O'HARE, OF SHARON, PENNSYLVANIA.

TIE AND RAIL-FASTENER.

1,095,590.

Specification of Letters Patent.

Patented May 5, 1914.

Application filed October 28, 1912. Serial No. 728,157.

To all whom it may concern:

Be it known that I, WILLIAM O'HARE, a citizen of the United States, residing at Sharon, in the county of Mercer and State 5 of Pennsylvania, have invented certain new and useful Improvements in Ties and Rail-Fasteners, of which the following is a specification.

My invention relates to an improved 10 metallic railway tie and means for securing the track rail thereto.

One of the objects of my invention is to provide a metallic railway tie which will maintain a fixed seat on the road bed.

15 Another object is the provision of such a tie with a recess therein in which a rail, when locked, is prevented from lateral movement on the tie.

A still further object is the combination 20 with the foregoing invention of improved means for locking the rail within its seat whereby any tie may be removed without disturbing the rails or loosening the fasteners or adjacent ties.

25 Still further objects and purposes of my invention will appear from an inspection of the drawings, the specification describing the same and the claim appended thereto, in which are set forth the combination of elements, arrangement of parts and novel structural details properly comprised within the scope of the same.

From the drawing in which is shown one of the embodiments of my invention, Figure 35 1 is a side elevation of a tie constructed according to my invention showing an anchor thereon, and an end cross sectional view of a rail locked in the tie. Fig. 2 is a fragmentary section of one of my ties showing 40 one of the two top recesses therein. Fig. 3, illustrating the same construction as Fig. 1, shows an end view of the tie and side view of the rail and locking means. Fig. 4 is a side elevation of my locking block. Fig. 5 45 is an end view of the block as shown in Fig. 4. Fig. 6 is a side view of the saddle in which the rail sits. Fig. 7 is an end view of the construction shown in Fig. 6.

Referring now to the several figures in 50 which like reference characters designate like parts, (1) represents a metallic tie, which, it must be understood, may be of any preferred construction, with the exception, however, that instead of providing bolt holes 55 at the top I roll into the tie during the construction a recess (1''), as shown in Figs.

1 and 2, in which the rail is adapted to sit. At either end of the tie is positioned the rail (2). The saddle (3) is slotted lengthwise in two directions, the horizontal slot (3') extending therethrough being adapted to embrace the flat top of the tie, and the vertical slot (3'') extending downwardly from the slot (3') embraces a part of the vertical portion of the tie. 65

As shown more clearly in Figs. 1 and 6, this saddle comprises on either side at the top a shoulder (6) below which is a recess (7), this recess being between the shoulder and abutment (8) in line with the shoulder (6). As shown in Fig. 1, this abutment (8) corresponds in size so that the abutments register with the recess (1'') in the tie. The locking block comprises the body portion (10), which in one side is provided with the recess (11). At the forward end of the block below the recess is a hole (9') in which a suitable pin (9) is adapted to fit. This pin which may be of a cotter type or any preferred construction is intended merely to 80 prevent the locking block from sliding out of the saddle.

As shown in Figs. 1 and 3, I slip onto the bottom portion of the tie two or more anchors (4), these anchors being provided 85 with an enlarged opening (4') corresponding in shape to the cross sectional shape of the base of the tie, but being, however, slightly larger so as to afford a limited play thereon. 90

My invention is employed as follows:— The tie is rolled with the recesses (1'') in either end, these recesses being separated to accommodate the gage of the track desired. The saddle is then slipped upon the tie so 95 that the abutments (8) register with the sides of each recess. The rail is then seated within the saddle so that the base (2') of the rail fits snugly in the recess (1'') and within the abutments (8). It will thus be 100 seen that the rail locks the saddle on the tie and prevents the lateral movement of the saddle on the tie. The locking blocks are now fitted in the under portion of the rail on each side so that the shoulder (6) fits within 105 the recess (11) of the locking block. The pin (9) thereupon being fitted in the opening (9') the block is locked against longitudinal movement in respect to the rail and the rail saddle and tie are locked together. One or more anchors are thereupon 110 placed on the base (1') of the tie and the

whole ballasted. The employment of the anchor presents a flat resisting surface to the lateral movement of the tie within the road bed, and at the same time by reason of its limited movement on the tie it permits of a slight movement of the latter inseparable from the proper construction of an easy riding track, without the anchor at the same time tearing a hole in the road bed.

- 10 By forming my saddle and tie separately, I am enabled to employ the most improved method of metallic tie manufacture in that while it is preferable to employ a rolled steel tie it would be impossible practicably 15 to roll with the tie a saddle of the form employed. Moreover, the better practice would call for a cast steel saddle, and for my invention, not only may the tie be rolled and the saddle cast, but the whole, when assembled 20 with the rail affords a compact and solid construction. In addition to this, should the saddle be fractured or otherwise damaged, it may be removed and a new one replaced without discarding the entire tie.
- 25 It will be seen from the construction of my device that where it becomes expedient

to remove a single tie all that is necessary is the withdrawing of the locking blocks and the taking out of the ballast from the tie, whereupon the tie and saddle will drop 30 away from the rail, permitting its removal and the replacement of another.

I claim—

In combination, a metallic tie having a flat upper surface provided at each end with a 35 rail receiving recess adapted to receive the base of a rail, of a saddle having longitudinally disposed grooves adapted to slide on said tie, said saddle being provided with a rail receiving recess approximately the size 40 of the rail receiving recess formed in the upper surface of said tie and registering therewith, a locking block provided with a locking pin adapted to secure said rail from longitudinal movement, as and for the purpose set forth.

In testimony whereof I affix my signature in presence of two witnesses.

WILLIAM O'HARE.
